UNITED STATES PATENT OFFICE.

THOMAS C. SISK, OF OAKLAND, CALIFORNIA.

RAILWAY TIE AND SPIKE.

1,071,361.

Specification of Letters Patent. Patented Aug. 26, 1913.

Application filed December 26, 1912. Serial No. 723,516.

To all whom it may concern:

Be it known that I, THOMAS C. SISK, a citizen of the United States, residing at Oakland, in the county of Alameda and State of California, have invented new and useful Improvements in Railway Ties and Spikes, of which the following is a specification.

This invention relates to railway construction, and particularly to an improved tie and spike for supporting and holding rails.

The object of the present invention is to provide a relatively inexpensive reinforced concrete tie, with an embedded rail-plate or chair, and a spike automatically locking with the chair, said plate having integral rigid means for preventing spreading of the rails.

20 The invention consists of the parts and the construction and combination of parts as hereinafter more fully described and claimed, having reference to the accompanying drawings, in which—

25 Figure 1 is a perspective view of the improved railroad construction. Fig. 2 is a transverse section through the tie in the plane of one of the transverse reinforcing rods. Fig. 3 is a central vertical section 30 through one of the rail chairs, showing a spike embedded and another before insertion in the chair.

In its illustrated embodiment, my improved construction comprises interchangeable, reversible rail chairs or blocks 2, each having a top plane or plate portion 3. The blocks are embedded in a concrete monolithic block or tie 4, with the top surfaces 3 in the plane of the top of the tie 4. The 40 rail chairs or blocks 2 are preferably formed of sufficient length to provide between their ends for the support of rails 5, the edges of the flanges of which are engaged by stops or upwardly projecting shoulders 6, formed integrally or otherwise upon the upper portion 45 of the blocks 2; these shoulders having the function of limiting the rails against spreading action.

For the purpose of preventing upward 50 movement of the rails, when adjusted upon the ties, I prefer to form in the blocks 2 core holes 7, each having divergent channels 8. Into the core holes 7 are insertible spikes such as I disclose in my Patent No. 55 1,031,878, dated July 9, 1912. These spikes are shown at 9 as having their shanks di-

vided to form separable prongs 10, which prongs, when inserted in the upper portions of the core holes 7 in the blocks 2 and then driven inwardly, will spread so as to automatically follow the curved, divergent channels 8.

For the purpose of obtaining a concrete tie, as 4, of sufficient rigidity to amply support the traffic, and yet provide for such a degree of flexure as is desirable, I extend longitudinally through the body of the tie 4 a series of substantially parallel reinforcing rods 11, arranged in upper and lower sets; the upper reinforcing rods bearing snugly against shoulders 12 formed on the blocks 2 and overhanging the upper rods 11, and in a similar manner the lower rods 11 abut against overhanging shoulders or lugs 13 formed upon the sides of the blocks 75 2. By this arrangement of the rail chairs or blocks 2, with their shoulders seating upon embedded reinforcing members 11, the load imposed upon the solid and substantial chairs is distributed between the concrete 80 structural material of the ties 4 and upon the reinforcing members 11; this combined support having sufficient longitudinal flexibility to provide a practical tie.

By using in combination with a tie, particularly designed for its reception, the peculiar spike 9, I obtain a railroad construction which effectually prevents spreading of the rails and at the same time provides a means for fastening the rail down upon 85 the tie, which means is so designed as to resist the normal tendency to work upwardly from the tie when loosened, and yet which spike can be very readily removed by the application of a suitable tool. 95

I have shown the block or rail chairs 2 of approximately T-shaped cross section, so that the upper reinforcing members 11 are spaced somewhat farther apart than the lower reinforcing members, and the blocks 100 are shown as transversely perforated, as at 14, for the insertion of transverse reinforcing rods 15 which may be headed up, as at 16, the heads lying approximate the plane of the side surfaces of the tie 4. 105

Having thus described my invention, what I claim and desire to secure by Letters Patent is—

1. In combination with railroad rails, blocks or rail seats arranged in a common 110 plane longitudinally and having lugs engageable with the edges of the rail flanges,

- a monolithic, cementitious tie in which the blocks are embedded with their upper surfaces in the plane of the top of the tie, reinforcing rods extending longitudinally through the tie, and abutting shoulders formed on the blocks for receiving a portion of the load imposed upon the blocks, said blocks having core holes for the reception of complementary spikes.
2. In combination with railroad rails, blocks or rail seats arranged in a common plane longitudinally and having lugs engageable with the edges of the rail flanges, a monolithic, cementitious tie in which the blocks are embedded with their upper surfaces in the plane of the top of the tie, reinforcing rods extending longitudinally through the tie, abutting shoulders formed on the blocks for receiving a portion of the load imposed upon the blocks, said blocks having core holes with divergent, intersecting channels, and spikes having divided shanks forming bendable prongs for following the channels in the blocks when driven in.
3. A railroad tie comprising a monolithic, cementitious body, iron rail chairs embedded at suitable locations in the body and having shoulders projecting from both sides, and longitudinal reinforcing rods arranged in upper and lower sets and seating against said shoulders for receiving a portion of the load imposed upon the chairs.
4. In a railway tie, a pair of axially coinciding spaced chairs having lugs on their rail-bearing surfaces for holding the rails against lateral movement and having shoulders on both of their longer sides, reinforcing irons positioned by and bearing against said shoulders, and a cementitious body structure inclosing said rods and all of said chairs with the exception of the rail-bearing surfaces thereof.

In testimony whereof I have hereunto set my hand in the presence of two subscribing witnesses.

THOMAS C. SISK.
